UNITED STATES PATENT OFFICE.

ROBERT L. WILLIAMS, OF NEWTON, MASSACHUSETTS, ASSIGNOR TO SUBMARINE SIGNAL COMPANY, OF WATERVILLE, MAINE, A CORPORATION OF MAINE.

Sounder for Submarine Signaling.

1,131,764.

Specification of Letters Patent. Patented Mar. 16, 1915.

Application filed December 9, 1909. Serial No. 532,197.

To all whom it may concern:

Be it known that I, ROBERT L. WILLIAMS, of Newton, in the county of Middlesex and State of Massachusetts, a citizen of the 5 United States, have invented a new and useful Improvement in Sounders for Submarine Signaling, of which the following is a specification.

Heretofore the vibrations of sounders for 10 submarine signaling purposes have been commonly excited either by direct impact, as of a clapper upon a bell or the like, or by magnetic attraction and release as by an electromagnet upon a suitably constructed 15 vibrator such as a bell or a diaphragm.

The sounder which I have invented consists essentially in two members, constituting a siren, which are submerged in a tank or similar means for containing water, and 20 are so constructed and arranged that the water is admitted from the tank into the inner member, and is ejected through ports in the outer member into the tank. I thus provide for a constant circulation of water 25 through my sounder or siren, as contrasted with attempts which have been previously made in which it has been necessary to carry the water through a pipe to the sounder from a special source of supply. It is also 30 a serious difficulty with apparatus of this class that an unbalanced pressure of water upon the outer member will create undesirable friction and interfere with the rapid rotation of the movable member. To ob- 35 viate this serious defect, I have in all cases so contrived and arranged my apparatus that the pressure exerted by the water or other fluid through the ports of the inner member upon the outer member is balanced, 40 and I regard this as an important and fundamental characteristic of my apparatus, and believe it to be broadly novel in the art.

My invention in one form comprises a rotary inner casing provided with ports and 45 inclosed in an outer casing also provided with ports, the whole combined with means for rotating the inner casing and with such accessories as may be desirable. But it is evident that my invention will also include 50 certain variations of construction, the essence of the invention being that the ports of one casing pass the ports of the other. In fact both may rotate provided they rotate in opposite directions or in different speeds

in the same direction. The exciting fluid 55 most conveniently used for submarine signaling is water but I do not mean to limit myself to water.

In using the term "inclosed" as applied to the position of the inner casing with relation to the outer casing, I do not mean that the outer casing actually surrounds the interior member on all sides but the two are so arranged that the ports of the inner member will be alternately opened and closed 60 because of their periodic registry with ports in the outer member or casing and the fluid will be forced from the inner casing through the ports in the outer casing, and the pressure of the fluid upon the outer casing 65 through the ports of the inner casing will be balanced in all cases.

I have shown in the drawings various structures illustrating some of the embodiments of my invention. As a matter of convenience I shall refer to the inner member, 70 that from which the water is expelled, as a cylinder, and the outer member through the walls of which it is expelled as a casing, though without this explanation those 75 terms may not always be apt.

Figure 1 is a side elevation of an apparatus embodying my invention located in a water tank which is shown in section. Fig. 2 is a vertical section of the apparatus of 80 Fig. 1, Fig. 2^a being a section of the cylinder and its casing taken on line 2^a—2^a of Fig. 2. Fig. 3 is a side elevation of a modification in which the cylinder is stationary and the casing revolves, Fig. 4 being a section thereof. Fig. 4^a is a fragmentary section showing ports of different shape from those 85 shown in Fig. 4. Figs. 5 and 6 show another modification in which both the casing and the cylinder revolve, but in opposite directions, Fig. 5 showing the parts in section 90 and Fig. 6 being a side elevation. Fig. 7 is a section showing a stationary cylinder, the casing being in the form of two disks, the ports being located in the side walls of both 95 cylinder and casing instead of in their periphery, Fig. 8 being a view on line 8—8 of Fig. 7. Figs. 9, 10 and 11 show the application of my invention to vessels.

Referring first to Figs. 1, 2 and 2^a, A is 100 the cylinder having a hub A¹ by means of which it is attached to the shaft B to turn therewith. The cylinder is provided with a

series of ports *a* which are preferably rectangular in plan and approximately wedge-shaped in cross section as shown in Fig. 2^a, being larger at the inlet than at the outlet. 5 Opposite the hub *A*¹, the cylinder has an opening *a*¹ through which the water or other fluid may flow into the cylinder *A*. The casing shown at *D* in these figures is a cylinder having an opening *d*¹ through its center, registering with the corresponding opening *a*¹ in the center of one side of the cylinder *A*. It also has ports *d* about its periphery corresponding with and adapted to register with the ports *a* in the periphery of 10 the cylinder. These ports are also preferably rectangular in plan and wedge-shaped in cross section but are smaller at the inlet than at the outlet. This casing is provided with a hub *d*² to inclose the hub *A*¹ of the cylinder and it also has a bearing *d*³ for the shaft *B*, this bearing being threaded at its outer end so that it may screw into the collar *D*¹ which is bolted to any suitable support. 15 Within the cylinder *A* I provide a number of blades *G* attached thereto to rotate therewith for the purpose of driving the fluid therefrom centrifugally as the cylinder revolves. Upon the outer end of the shaft *B* is carried a pulley *B*² by which power may be applied to the shaft *B* to rotate the cylinder *A*. 20 The apparatus may be attached to any convenient portion of a ship's interior, or other convenient place where the sounder is to be used. In practice such a sounder is preferably located in a water tank forming an inclosure inside of the ship of sufficient size to allow the proper operation of the sounder, though it may be mounted in a water ballast tank (see Figs. 9 and 10). The ship's wall or hull is shown at *C* (Fig. 1) and the wall of the tank to which the apparatus is attached is indicated in all views 25 at *C*¹, the bottom of the tank being marked *C*² and the top *C*³. The tank is preferably made in one casting, its top and bottom being attached to the ship's side by brackets *c* of suitable shape and bolted to the ship's side. It has a suitable opening through 30 which it may be filled with water. In this form of my invention I usually provide a drain pipe *E* which is connected to the two sides of the chamber in which the cylinder rotates by branches *e* and leads out of the tank so as to prevent any accumulation of 35 pressure in the chamber containing the cylinder. Such pressure might result from a leakage of water from the ports leading from the inner cylinder and where the pressure was very great an accumulation of pressure between the moving parts would necessarily result in considerable friction. The 40 element of friction is one which this device in its various forms is intended to eliminate

so far as possible and hence to eliminate friction at this point I use the pipe referred to by which this liquid may pass off under pressure. I also provide a pipe *F* connected to the same chamber by branches *f*, *f*, and 75 leading up above the water level through the top of the tank if necessary so that air may freely enter the chamber to take the place of the water which drains out through the pipe *E*. 75

The apparatus being located in a water tank as above referred to, the cylinder is of course flooded with water when still. The rapid action of the blades *G* during the rotation of the cylinder *A* causes the delivery of the water by centrifugal force through the openings *a* and *d*, the rapid passage of the openings by each other cutting off the streams of water into jets, there being a continuous series of effluxes and stoppages which when sufficiently rapid cause the production of sound. As the water is driven out other water takes its place through the openings *a*¹, *d*¹ to be similarly expelled. The pitch of the note sounded by 90 the device depends upon the speed of rotation of the cylinder and the number of openings.

The wedge-shaped character of the openings I also find of considerable value in 95 reducing the friction of the jets as they pass through the cylinder giving a free clearance as they escape from the casing and a sharp cut-off at the desired instant. I have shown the number of ports in the 100 moving member as being equal to the number in the stationary member as this is preferable. If they are not equal or a multiple of each other the best results will not be secured as the ports will not open and close simultaneously. When the ports of the cylinder are not opposite the ports of the casing the pressure of the water in the cylinder acts against the rim of the casing. But by the arrangement I have shown this 105 pressure is radial and balanced and hence in no way increases the friction of the moving parts for there will be no tendency of the water pressure to drive any moving part against another part which would result 110 necessarily in friction. On the contrary the pressure is exerted radially over the axis of the device in most forms of my invention or on opposite sides of the device so that 115 pressure is equal in all directions. 120

When systematic or code signaling of any kind is desirable without stopping the rotation of the cylinder the casing may be provided with a ring *L* which may be moved on the casing to close the ports *d* and so stop the efflux of water and the sound produced thereby as shown in Fig. 1 or be moved to open the ports *d* as shown in Fig. 2 and allow the water to escape. I have shown means for moving this ring in Fig. 1 where 125 130

L¹ is a hand lever the upper end of which passes up through the top of the tank, its lower end being forked to straddle the shaft bearing d⁵ and pipe E, the extremities of the fork being pivoted as at l to lugs l¹ attached to the lower part of the tank wall C¹. Links L² pivoted both to the forked portions of the lever L¹ and to both sides of the ring L so connect these parts that a movement of the lever from its position in Fig. 1 to the left will withdraw the ring into the position shown in Fig. 2.

It will be seen that by moving the handle to open the ports the apparatus will sound and continue to sound until the ports are closed. These periods of opening and closing may be of any desired length of time according to a predetermined code, and while the lever is shown as moved by hand, it is evident that it may be otherwise moved if desired.

In Figs. 3 and 4 I have shown another form of my invention in which instead of relying upon the blades G upon the interior of the moving cylinder to eject water by centrifugal force from the interior of the apparatus and simultaneously to draw in a fresh supply, I use a pump which forces liquid into the cylinder thus ejecting its contents therefrom. H is the pump, h being the usual air chamber. The pump is fed by the pipe H¹ from the tank in which the wheel is suspended. Beyond the air chamber the pipe divides itself into two parts, one part H² returning to the tank, the other part H³ being connected with the interior of the cylinder as shown in Fig. 4. H⁴ is a three-way cock of ordinary construction whereby the water after passing the pump may be turned either through the pipe H³ to the sounder or back into the tank H² as may be desired. By this construction systematic signaling may also be carried on, the apparatus producing sounds of a length controlled by the three-way valve and depending on whether water from the pump is forced through the pipe H³ into the cylinder or the pipe H² back into the tank. This valve may be controlled in such way as seems best. In these views I have also shown a modification of the construction of cylinder and casing. The casing is similar to that shown in Figs. 1 and 2 in so far as it surrounds the chambered cylinder on its outer side and periphery, but it differs from that casing in that it is cap-shaped and closed at the center, its outer wall being indicated at D¹⁰ and its periphery at D²⁰, its ports being marked J¹⁴. In this case, however, the cylinder A²¹ is stationary and is furnished with a flange D² by which it is bolted to the wall C¹ and a hub a² to serve as a bearing for the shaft B. Openings are shown at e¹ which will relieve any pressure of water between the cylinder and the casing

thus performing the function of the pipe e in the form of my invention shown in Fig. 1. The casing is mounted on the shaft B which carries the pulley B² as before. A collar b pinned to the shaft B serves as a thrust bearing against the inner wall of the cylinder A¹⁵. In this case a pressure is maintained by the pump H independent of the speed of rotation of any of the parts, whereas in the device shown in Figs. 1 and 2 the effectiveness of the apparatus depends upon the speed of rotation because the speed of rotation of the blades G controls the pressure by which the water is expelled. If the ports in this form of my device are shaped and arranged as shown in Fig. 4 the pressure from the pump will be sufficient to drive the outer casing owing to shape of its parts and their direction in relation to the direction of the liquid as it issues from the cylinder. In this view the ports are lettered a¹⁰, d¹⁰.

In Figs. 5 and 6 I have shown another form of my invention in which both the interior and exterior parts rotate though in opposite directions. To this end the shaft B upon which the interior cylinder A is mounted has at its outer end a beveled gear B³ to which power is transmitted through the gear B⁴ from the pulley B²¹ on shaft B⁵ mounted in suitable bearings upon the outer wall of the tank. A gear d⁴ which is mounted on a sleeve d⁵ on the outer end of which is carried the casing is also in mesh with the gear B⁴. A long bearing d⁶ bolted to the wall C¹ of the tank supports the apparatus. In this case the inner cylinder is provided with blades G by which the water is expelled from the cylinder through the openings in the periphery of both cylinder and casing as in Figs. 1 and 2, water being drawn in through the opening a¹⁵ in the center of the cylinder. The blades in this case are shaped and arranged like those shown in Fig. 2^a between the central opening and the rim containing the ports. The casing in this instance has no outer or inner casing wall.

In Figs. 7 and 8 I have shown still another form of construction in which the interior cylinder A¹⁰ is stationary, being mounted on a supporting bracket A², this cylinder having ports a¹⁶ in its sides. The outer casing comprises two disks D¹, each having a hub D⁵ pinned to the shaft B carrying the pulley B² to turn therewith, these disks being provided with side ports d⁷ to register with the ports a in the side walls of the cylinder. It will be seen that by having two disks, any end thrust along the shaft due to the pressure of the water through the ports of the cylinder when they are closed is balanced. Water is supplied to this device by a pump as before though in this case I have not shown the three-way

valve but merely a circulating system from the tank to the pump and out again through the apparatus.

It will be seen from these various embodiments of my invention that it is capable of considerable variation in construction. Nor have I shown all its forms of embodiments.

As to the mode of use of the invention it may be located in a special water tank as shown in the earlier views or as shown in Figs. 9 and 10 where my apparatus K is belted to a motor J, the sounder being located in a tank in the fore peak of the ship; Fig. 11 shows the apparatus as it may be mounted on a submarine boat. Here it is in the open water, the motor J being mounted directly on the shaft B.

It will be appreciated that in a device of this kind where great rapidity of rotation is required friction must be reduced to the least possible amount and it will be noted upon examination of the forms of my invention shown that so far as possible friction due to end thrust of the shafts has been reduced to a minimum by having the port openings at right angles to the shaft except in Figs. 7 and 8 where the ports in the rotating casing are in both the sides thus balancing each other.

30. What I claim as my invention is:

1. A sounder for submarine signaling comprising a liquid-filled tank, two concentric members submerged therein, one member being within the other, the inner member being chambered, each member having ports, the ports of one member being located to register with the ports of the other member, one of said members being adapted to be rotated with relation to the other member, said ports being located on opposite sides of said members whereby when said ports register the pressure within said members will be released in opposite directions.

2. A sounder for submarine signaling comprising a liquid-filled tank, two concentric members submerged therein, one member being within the other, the inner member being chambered, each member having ports, the ports of one member being located to register with the ports of the other member, one of said members being adapted to be rotated with relation to the other member, said ports being located on opposite sides of said members whereby when said ports register the pressure within said members will be released radially.

3. A sounder for submarine signaling comprising a liquid-filled tank, two concentric members submerged in said tank, one member being within the other, the inner of said members having a chamber therein, and means for rotating one of said members with relation to the other, said members having ports adapted to register with each other, said chamber having an inlet to receive

liquid from said tank, and means for causing the contents of said tank to circulate through said chamber and out said ports.

4. A sounder for submarine signaling comprising a liquid-filled tank, two concentric members submerged therein, one member being within the other, the inner member being adapted to be rotated, each of said members having ports adapted to register with those of the other, the inner member having a chamber, and means whereby the contents of said tank may be circulated through said chamber and said ports, said members being located in close relation to each other, the outer member being provided with pipe connections leading from the space between said members adapted to release pressure in said space.

5. A sounder for submarine signaling comprising a liquid-filled tank, two concentric members submerged therein, one member being within the other, the inner member being adapted to be rotated, each of said members having ports adapted to register with those of the other, the inner member having a chamber, and means whereby the contents of said tank may be circulated through said chamber and said ports, said members being located in close relation to each other, the outer member being provided with means whereby increase of pressure in the space between said members may be prevented, said means comprising a connection leading from the space between said members to a point outside the tank.

6. A sounder for submarine signaling comprising a liquid-filled tank, two concentric members submerged therein, one member being within the other, the inner member being adapted to be rotated, each of said members having ports adapted to register with those of the other, the inner member having a chamber, and means whereby the contents of said tank may be circulated through said chamber and said ports, said members being located in close relation to each other, the outer member being provided with means whereby increase of pressure in the space between said members may be prevented, said means comprising a connection leading from the atmosphere to the space between the members adapted to supply air thereto.

7. A sounder for submarine signaling comprising a liquid-filled tank, two concentric members submerged therein, one member being within the other, the inner member being adapted to be rotated, each of said members having ports adapted to register with those of the other, the inner member having a chamber, and means whereby the contents of said tank may be circulated through said chamber and said ports, said members being located in close relation to each other, the outer member being provided

with means whereby increase of pressure in the space between said members may be prevented, said means comprising a connection leading from the atmosphere to the space between the members adapted to supply air thereto, and a connection leading from the space between said members to a point outside the tank whereby increase of pressure in the space between the members will be prevented.

8. A sounder for submarine signaling comprising a liquid-filled tank, two concentric members being submerged therein, one member being within the other, the outer member being stationary, means for rotating the inner member, the inner member having a chamber and said members having ports adapted to register, means for supplying said chamber with liquid from said tank, and means for forcing the liquid from said chamber out through said ports when said ports are in register, and means adapted to prevent the increase of pressure between said members, as described.

25 9. A sounder for submarine signaling

comprising a liquid-filled tank and two concentric members submerged therein, one of said members being within the other, the inner member being chambered, each member having discharge ports adapted simultaneously to register with the discharge ports of the other member, in combination with means whereby the intermittent registration of said ports is effected and liquid is discharged under pressure therethrough. 30 35

10. A sounder for submarine signaling comprising a tank filled with liquid under pressure and two concentric members located therein, one member being located within the other, the inner one of said members being provided with a chamber, said members having ports adapted to register with each other, and means for forcing the water of said tank into said chamber and out through said ports and into said tank when said ports are in register, as described. 40 45
